ABSTRACT OF THE DISCLOSURE

This invention relates to devices for producing sheets and tubes of fibrous cement or the like, in which a web of plastic mass of fibrous cement is wound in a plurality of layers on to a sizing roll or a mandrel, respectively, dewatered and compacted.

BACKGROUND OF THE INVENTION

In the sheet producing machines which have been hitherto used in practice the sizing roll is rotated by a stationarily mounted breast roll, which is driven at constant speed by a motor and supports the sizing roll mounted on vertically movable supporting arms, through the intermediary of the web of fibrous cement fed between the breast roll and the sizing roll by a likewise driven endless felt belt and transferred to the latter roll, and through the coiled layers of web material already produced on the sizing roll. The peripheral speed of the sizing roll, the outer diameter of which becomes increasingly larger with the growing wall thickness of the hollow fibrous cement cylinder under construction, is equal to that of the breast roll.

In tube producing machines the mandrel is driven in a similar manner by the endless felt belt through the web of fibrous cement fed by the latter and through the coiled layers formed on the mandrel.

In the friction drive of the sizing roll or the mandrel, respectively, which in practice is generally used both in sheet and tube producing machines, the mass of fibrous cement is effective as a power transmitting medium in that a thrust present in the direction of rotation of the breast roll and in the feed direction of the felt belt is acting on the web of fibrous cement being fed and on the already coiled layers of web material and puts the sizing roll or the mandrel into rotation. The thrust must not exceed a certain value which is dependent on the kind of fibrous cement mass being processed as well as on the thickness of the web of fibrous cement on the felt belt, since otherwise there is a risk of structural distortions occurring in the web of fibrous cement to be coiled and in the already produced coiled layers, and of the individual coiled layers not being uniformly compacted, matted and dewatered. This has to be taken into consideration when rating the speed at which the web of fibrous cement is running on to the sizing roll or the mandrel. A faster production speed as is desired for increasing the output and for economical reasons could hitherto not be realized because the accomplishment of unobjectionable finished products would then be no longer ensured.

Difficulties concerning production engineering are caused above all in the manufacture of thick-walled hollow cylinders and tubes of fibrous cement by the fact that due to the thrust exerted by the breast roll and the felt belt on the mass of fibrous cement the outer coiled layers are not produced with the same homogeneity and the same surface finish as the inner coiled layers. It has been found in practice that particularly the edge portions of

2

the finished sheets of fibrous cement and the end portions of the tubes of fibrous cement are not solidly enough compacted.

SUMMARY OF THE INVENTION

It is the object of the present invention to shorten the production time for the hollow cylinders of fibrous cement intended for the production of sheets or to be manufactured as tubes and to improve, at the same time, the quality of the finished articles, especially of the thick-walled finished articles.

This object is achieved according to the invention by providing a method of producing sheets and tubes of fibrous cement or the like, which comprises the steps of winding a web of plastic mass of fibrous cement in several layers on to a sizing roll or a mandrel, respectively, dewatering and compacting said web and transmitting during the winding, dewatering and compacting operations a torque, preferably a torque becoming increasing larger with the growing wall thickness of the hollow cylinder of fibrous cement under construction, directly to the sizing roll or the mandrel, respectively, so that during the winding operation the sizing roll or the mandrel, respectively, exerts a force on the mass of fibrous cement that reduces or cancels the thrust exerted on the mass of fibrous cement by a breast roll driven at constant speed and by a web transporting belt or becomes effective as tensile force when further increasing the driving torque, by which tensile force the fibres oriented in the winding direction and the individual coiled layers are prestressed.

Since thus the mass of fibrous cement is at least partly or even fully relieved, during the winding operation, from the thrust acting in the winding direction, the speed of building up the hollow cylinder of fibrous cement can be increased without thus involving the risk of damaging by deformation the web of fibrous cement running on to the sizing roll or the mandrel and the coiled layers already formed. By the method according to the invention the fed web of fibrous cement is wound on to the sizing roll or the mandrel, firmly pressed together with the previously formed coiled layers while being dewatered, and connected with them to form a hollow cylinder of fibrous cement which is uniformly homogeneous in all layers and also of compact structure in the two end portions. Generally, the advantages of the method as proposed by the invention come into play best when the torque driving the sizing roll or the mandrel becomes larger with the growing wall thickness of the hollow fibrous cement cylinder under construction. This ensures that the outer layers of web material are wound on the sizing roll or the mandrel in as tight and firm a manner as the inner layers so that the finished hollow cylinders of fibrous cement show no differences in structure and compactness. In some cases it may be expedient for the condition of the material to be processed and for its filling material as well as for the pressure action on the sizing roll, which is necessary in particular cases, to drive the sizing roll or the mandrel with a constant or even decreasing torque during the whole winding operation.

If the torques driving, on the one hand, the breast roll and the felt belt and, on the other hand, the sizing roll or the mandrel are adjusted to one another so that the force exerted on the mass of fibrous cement by the sizing roll or the mandrel is greater than the thrust with which the breast roll and the felt belt act on the fibrous cement material, then the fibres lying in the longitudinal direction of the web of fibrous cement and the individual coiled layers will be given an optionally adjustable initial tension. In this way, finished products are obtained that are distinguished by increased strength.

The method as proposed by the invention can be carried out in various ways. One of the possibilities coming

into question for practical operation consists in controlling the transmission of torque in dependence on the variation of speed of the sizing roll or the mandrel that occurs during the growing of the wall thickness of the hollow cylinder of fibrous cement under construction. In this case the sizing roll or the mandrel may be driven either by an electric motor or a hydraulic motor and the driving power may be transmitted by a Cardan shaft, a flexible shaft, a V-belt drive or a similar transmission with or without interposition of a mechanical or magnetic clutch.

In the case of an electrical drive, it is expedient to use as a driving motor for the sizing roll or the mandrel an electric motor the current consumption of which adjusts itself automatically in accordance with the rising torque with the aid of a tacho-generator connected to the shaft of the breast roll or of the driving motor of the breast roll. But the electric driving motor may also be controlled, for example, by means of a camshaft connected with the shaft of the sizing roll or the mandrel through a disengageable clutch.

In the case where a hydraulic drive is used for the sizing roll or the mandrel, regulating means serving to influence the hydraulic fluid circuit of the hydraulic motor may be controlled either also in dependence on the speed of the shaft of the sizing roll or the mandrel e.g. by means of a centrifugal governor, a camshaft or the like, or in dependence on the lifting motion of swinging arms supporting the sizing roll or the mandrel.

According to a further suggestion of the invention, a direct control of the regulating means in the hydraulic fluid circuit of the hydraulic motor by means of a time switch may be provided.

Brief description of drawings

Several embodiments of devices for carrying out the method according to the invention will now be described by way of example and with reference to the accompanying drawings, in which:

FIG. 1 is a schematic side elevational view of the details of a sheet producing machine with an electric motor drive for the sizing roll that are necessary for the understanding of the invention;

FIG. 2 is a circuit diagram of the self-regulating electric motor drive for the sizing roll;

FIGS. 3 and 4 are a schematic side elevational view and a schematic front elevational view, respectively, of the sizing roll and the breast roll, showing a hydraulic drive for the sizing roll;

FIG. 5 is a schematic side elevational view showing the control of the hydraulic drive for the sizing roll with the aid of a centrifugal governor;

FIG. 6 is a layout diagram of the hydraulic drive of FIG. 5;

FIG. 7 is a schematic side elevational view showing the control of the hydraulic drive for the sizing roll in dependence on the lifting motion of the swinging arms supporting the sizing roll;

FIG. 8 is a layout diagram of the hydraulic drive of FIG. 7, and

FIG. 9 is a schematic side elevational view showing the control of the hydraulic drive by a time switch.

Description of specific embodiment

FIG. 1 shows a sheet producing machine which comprises, as is customary, a winding or sizing roll 1 having a shaft 2 rotatably mounted in bearings 5 on two supporting arms 4 vertically swingable about fixed fulcrums of a frame 3, and a breast roll 6 having a shaft 7 mounted in bearings of the frame 3 so as to be rotatable but immovable in height. The vertically movable sizing roll 1 bears against the breast roll 6 which is provided with a smaller diameter, and in addition to the force exerted by its dead weight it is firmly pressed against the breast roll 6 by an external force. For this purpose two hydraulical-

ly or pneumatically operated working cylinders 9 are provided which are pivoted to arms 3a of the frame 3 and have piston rods 10 hingedly connected to the ends of the double lever-type supporting arms 4 remote from the sizing roll 1. The additional contact pressure of the sizing roll 1 can be optionally adjusted according to requirements by varying the pressure fluid supply to the working cylinders 9.

A web of fibrous cement can be conveyed to the sizing roll 1 by means of a conveniently driven endless felt belt 11 arranged to travel in a known manner over one or more containers (not shown) in which sieve drums and couch-rolls are disposed for applying a plastic mass of fibrous cement on to the downwardly directed side of the lower run of the endless felt belt 11, couching the applied mass and precompressing it.

The upper run of the felt belt 11 is arranged to pass over a suction box 12 serving to suck part of the moisture out of the web of fibrous cement. On the downstream side of the suction box 12 the felt belt 11 is advanced to the sizing roll 1 over guide rollers 13 and then passed through between the sizing roll 1 and the breast roll 6. When passing through between the sizing roll and the breast roll the felt belt transfers the web of fibrous cement, which is positioned on its upper side, to the sizing roll 1 on which a hollow cylinder 8 of fibrous cement is formed of the individual coiled layers of web material.

The felt belt 11 is passed on over the breast roll 6 and after having been passed round a return roller 14 it is guided over a cleaning device which may comprise, for example, felt beaters 15 and spray nozzles, and in a clean state it is passed over a plurality of guide rollers 16 to reach again the sieve cylinders from which it can then take up again wet mass of fibrous cement.

The breast roll 6 is driven by a variable electric motor 80 mounted on a bracket and having a reduction gearing 81. A belt 82 transmits driving power to the shaft 7 of breast roll 6. The speed of the driving motor and thus the peripheral speed of the breast roll can be adjusted in accordance with the kind of fibrous cement material to be processed and with the kind of the products to be manufactured.

The above-described details of the sheet producing machine are known. In accordance with the invention a special drive is provided for the sizing roll 1, which can be realized in various ways, as will be hereinafter explained more specifically by reference to exemplified embodiments.

In FIGS. 1 and 2 the driving motor 80 of the breast roll 6 drives through a belt 17 a tacho-generator 18 capable of generating a constant alternating voltage corresponding to the constant motor speed. The alternating voltage of the tacho-generator 18 can be transformed into a direct voltage by a rectifier 19 (FIG. 2). The direct voltage which is proportional to the speed of the driving motor 80 is used for energizing a generator 20, the armature voltage of the generator 20 being proportional to the speed of the electric motor 80 which drives the breast roll 6 and the tacho-generator 18 and regulable by means of a regulating resistance 21. The actual number of revolutions per minute of the breast roll 6 can be read on a voltmeter 22 calibrated as a speed indicator and is accurately adjustable by means of a regulating resistance 23 to the speed given in each case by the breast roll 6.

The sizing roll 1 is driven by a D.C. motor 24 which can be energized by the voltage generated by the generator 20. A driving motor 25 is connected to a power supply system which feeds also the driving motor 80 of the breast roll 6. A rectifier 26 having a regulating resistance 27 is connected to the power supply system to produce a direct voltage of, for example, 180 volts which serves for exciting the field voltage of the D.C. motor 24, also in this case a regulating resistance 28 being connected in the lead. As the armature voltage of the generator 20 is proportional to the speed of the motor 80 driving the breast roll 6, the power transmission from the driving motor 24 to the sizing roll 1 is dependent on the speed of the driving motor

80 for the breast roll and of the tacho-generator 18 connected to said motor 80.

When the web of fibrous cement is wound in several layers on to the sizing roll 1, then the outer diameter of the sizing roll 1, which results from the jacket diameter of the sizing roll 1 and from the coiled layers applied thereto, grows with each revolution. Since the sizing roll 1 is not to vary its peripheral speed, the speed of the electric motor 24 driving the sizing roll will have to slightly decrease with each revolution. The D.C. motor 24 is not capable of varying its speed by itself. The decrease of speed is brought about by the fact that the sizing roll 1 or the coiled layers already applied thereto are or respectively are in frictional engagement with the web of fibrous cement which is fed by the felt belt 11, so that, consequently, the peripheral speed of the sizing roll 1 must be the same as that of the breast roll 6.

Due to the decrease of the speed of the D.C. motor 24 driving the sizing roll 1, the counter-electromotive force in the D.C. motor 24 decreases whereas the current consumption through the armature of the D.C. motor increases accordingly. With the increased power consumption, which is controlled by the voltage of the tacho-generator 18 and by the mode of operation of the generator 20, the D.C. motor 24 produces an increasingly augmenting torque as is required for winding the outer layers of web material as tightly and firmly on the sizing roll 1 as the inner layers.

The D.C. motor 24 is arranged on a plate-like support member 29 secured to one of the vertically movable supporting arms 4 for the sizing roll 1. The D.C. motor 24 drives a worm gear comprising a worm 31 and a worm wheel 32 through a V-belt drive 30. The worm 31 and the worm wheel 32 are enclosed in a gear housing 33 which is likewise arranged on the plate-like support member 29. From a V-belt pulley 34 seated on a common shaft with the worm wheel 32, the torque is transmitted to the sizing roll 1 through an endless V belt 35 and a V-belt pulley 36 seated on the shaft 2 of the sizing roll 1.

In FIGS. 3 and 4 the sizing roll 1 is driven by a hydraulic motor 37 which drives the shaft 2 of the sizing roll 1 through a reduction gearing 38. Pressure fluid is supplied to the hydraulic motor 37 through a conduit 39 and returns to a pressure oil tank through a conduit 40.

The layout diagram of the pressure oil circuit is apparent from FIG. 6 and will be explained in detail hereinafter. In the embodiment of FIGS. 5 and 6 a worm wheel 41 is mounted on the shaft 2 of the sizing roll 1 and drives a spindle 43 through a worm 42. Hinged to the spindle 43 are centrifugal weights 44 the deflection of which is transmitted to a stop arm 46 through a rotatable ring 45. The stop arm 46 is displaceably guided on the spindle 43 by means of a guide sleeve 47 and serves as control element for a feeler lever 49 of a pressure-regulating valve 50, which lever is provided with a sliding roller 48. A spring 51 of the pressure-regulating valve 50 causes the sliding roller 48 of the feeler lever 49 to bear against the stop arm 46. With increasing wall thickness of the hollow cylinder of fibrous cement being under construction on the sizing roll 1, the speed of the sizing roll 1 decreases whereby the centrifugal weights 44 come down and thus actuate the pressure-regulating valve 50 through the stop arm 46.

The control that results therefrom for the hydraulic drive is described as follows by reference to the layout diagram of FIG. 6: An electric motor 52 drives an axial piston pump 53 of known construction which is provided with an swingable part 54 for adjusting the stroke volume. Adjustment of the swingable part 54 is effected by means of a pressure regulator 55 which is operatively connected with the pressure-regulating valve 50. The pump 53 is arranged to deliver pressure oil through the feed conduit 39 to the hydraulic motor 37 which is thereby put into rotation. The oil issuing again from the hydraulic motor 37 through the conduit 40 is returned to the tank 58 via a preloading valve 56 and a filter 57.

The preloading valve 56 has the function of generating

a small counter pressure in the hydraulic motor 37 to attain smooth running. In case the hydraulic motor 37 is blocked, the oil stream delivered by the pump 53 flows directly off to the tank 58 through a pressure relief valve 59. As the pressure slowly rises due to the augmenting driving torque, an adjusting piston of the pressure-regulating valve 50 clears a cross-sectional area of the valve and permits a small oil stream to arrive at a spring-loaded adjusting piston 55a of the pressure regulator 55. If the volume of this oil stream is smaller than the passage through a by-pass throttle 60, then no adjustment of the stroke volume of the axial piston pump 53 is effected so that the driving speed of the hydraulic motor 37 is not varied. But as soon as the quantity of oil flowing to the pressure regulator 55 becomes so large that it can no more flow off through the by-pass throttle 60 without pressure loss, then the oil stream will adjust the piston 55a of the pressure regulator 55 against the action of a biased spring 55b and thus reduce the stroke volume of the pump 53. The pump now delivers a smaller quantity of pressure oil per unit of time, which results in a decrease of the driving speed of the hydraulic motor 37.

If for some reason or other the torque should decrease again, then the pressure in the conduit 39 to the hydraulic motor 37 would also drop. The adjusting piston of the pressure-regulating valve 50 then moves into the shutoff position and there flows no more pressure oil to the adjusting piston 55a of the pressure regulator 55. The spring 55b of the pressure regulator 55 can thus restore the adjusting piston 55a into the position in which the pressure oil is led off through the by-pass throttle 60. In this manner the swingable part 54 of the pressure oil pump 53 is swung out again to allow increased delivery of the pump.

This would take place, in particular, when the finished sheet of fibrous cement runs off the sizing roll 1. But then a three-way valve 61 which is operable through a limit switch will take over immediately. The basic adjustment of the pressure regulator 55 is obtained by prestressing the spring 55b of the adjusting piston 55a or through the adjustment of the spring 51 of the pressure-regulating valve 50. The three-way valve 61 which is incorporated in the feed conduit 39 serves for shutting down the hydraulic motor 37 in that it deviates as a hydraulic switch the oil stream from the hydraulic motor 37 and returns it to the tank 58 while by-passing the hydraulic motor 37. It would be suitable to operate also the three-way valve 61 by means of the contactor for the driving motor of the breast roll 6 through the intermediary of an auxiliary switch so that in the event of trouble the hydraulic motor is stopped immediately. But, as a matter of course, the hydraulic motor 37 can also be stopped by switching off the electric driving motor 52.

In the arrangement according to FIGS. 7 and 8 the control of the regulating means disposed in the pressure oil circuit is derived from the lifting movement of the supporting arms 4 for the sizing roll 1. For this purpose a cam rail 62 which is engaged by the sliding roller 48 of the feeler lever 49 of the pressure-regulating valve 50 is secured to the end of one of the two supporting arms 4 remote from the sizing roll 1. As the wall thickness of the hollow cylinder of fibrous cement on the sizing roll 1 increases, the cam rail 62 is moved downwardly thereby to operate the feeler lever 49 of the pressure-regulating valve 50. In this case, analogously, the same control operations are caused to take place in the pressure oil circuit as they have been described in detail when explaining the layout diagram of FIG. 6.

FIG. 9 shows an exemplified embodiment for the direct control of the regulating means of the pressure fluid circuit by means of a time switch such as an electrically operated clock which is accommodated in a common housing 63 with an interlocking contactor and a time-delay relay. The layout of the oil circuit and the associated regulating means are substantially the same as in FIGS. 6 and 8. The only difference of the arrangement according

to FIG. 9 consists in that a two-way valve 64 and a control pump 65 with an electric driving motor 66 are connected in the pressure oil system instead of the by-pass throttle 60 and the pressure-regulating valve 50, respectively. The electric driving motor 52 for the piston pump 53 of variable stroke volume and the electric driving motor 66 of the control pump 65 can be switched on simultaneously by means of a master contactor controller.

To one of the supporting arms 4 for the sizing roll 1 a cam rail 67 is secured which is arranged to operate a limit switch 68 when the finished sheet of fibrous cement runs off the sizing roll 1 and when the sizing roll 1 goes down toward the breast roll 6.

The limit switch 68 sets going the clock and simultaneously actuates the interlocking contactor which closes the two-way valve 64. The control pump 63 now delivers a small constant quantity of oil to the pressure regulator 55 which corresponds with regard to construction and operation to the pressure regulator 55 of the arrangement according to FIG. 6. The piston 55a of the pressure regulator 55 moving upwardly against the action of the preloaded spring 55b adjusts the swingable part 54 of the piston pump 53 of variable stroke volume so that the pump feeds pressure oil to the hydraulic motor 37 and transmits through the reduction gearing 38 a torque with an appropriate number of revolutions to the sizing roll 1. As the control pump 65 is acting during the whole operating time of the time switch with an increasingly augmenting pressure on the piston 55a of the pressure regulator 55, the driving torque generated in the hydraulic motor 37 becomes increasingly greater.

Switching off the time switch is effected by a microswitch 69 incorporated in a device 70 for measuring the wall thickness of the hollow cylinder of fibrous cement being under construction on the sizing roll 1. The device for measuring the thickness operates in a known manner by means of a feeler roller adapted to travel along the surface of the hollow cylinder of fibrous cement.

When upon reaching the real size of the hollow cylinder of fibrous cement the microswitch 69 is operated and switches off the time switch, the interlocking contactor is actuated which causes the impulse for severing the finished hollow cylinder of fibrous cement to be generated. At the same time the two-way valve 64 is moved by the interlocking contactor into the open position in which the oil is displaced from the valve housing and forced back into the tank 58 by the spring 55b of the pressure regulator 55. The three-way valve 61 incorporated in the pressure oil circuit, which is not shown in FIG. 9, is also operated so that the oil supply to the hydraulic motor 37 is interrupted and the oil is caused to flow off into the tank 58.

After having been switched off, the time switch returns automatically into the zero position. Switching it on again is effected by the limit switch 68.

With the aid of the time-delay relay accommodated in the housing 63 and by establishing a connection between the same and the microswitch 69 it is possible to temporarily adjust the individual operations to one another as desired in order to meet practical requirements.

I claim:

1. An apparatus for manufacturing plastic, fibrous cement sheets and tubes comprising:

- (a) a vertically movable winding roll having a surface for carrying said fibrous cement,
- (b) a breast roll located adjacent said winding roll,
- (c) means directing an endless belt between said winding roll and said breast roll,
- (d) a first driving means for driving said breast roll at a constant peripheral speed,
- (e) a second driving means for providing a driving power to impart a peripheral speed to said winding roll,
- (f) said endless belt carrying a web of a mass of plastic, fibrous cement and feeding layers of said web to form a wall of said mass onto said winding roll

60

65

70

75

whereby said wall has an increasing thickness as the wall is formed,

- (g) a means pressing said winding roll against said breast roll and compacting said web onto said winding roll,
- (h) said second driving means including a control means for varying the said driving power as a function of said increasing thickness to thereby control said peripheral speed of said winding roll.

2. Apparatus for manufacturing plastic, fibrous cement sheets and tubes, comprising:

- (a) a vertically movable winding roll having a shaft and a surface for carrying said fibrous cement,
- (b) a breast roll located adjacent said winding roll,
- (c) means directing an endless belt between said winding roll and said breast roll,
- (d) a first driving means for driving said breast roll at a constant peripheral speed,
- (e) a second driving means for providing a driving power to impart a peripheral speed to said winding roll,
- (f) said endless belt carrying a web of a mass of plastic, fibrous cement and feeding layers of said web to form a wall of said mass onto said winding roll whereby said wall has an increasing thickness as the wall is formed,
- (g) a means pressing said winding roll against said breast roll and compacting said web onto said winding roll thereby forming a hollow, fibrous cement cylinder by subjecting said wall to shear forces as the endless belt passes between the said winding roll and said breast roll when said rolls have different peripheral speeds,
- (h) said second driving means including a control means for varying said driving power,
- (i) said control means including a means for monitoring said increasing thickness of said wall,
- (j) said control means further including a means responsive to said monitoring means for varying the said driving power as a function of said increasing thickness to thereby control the amount of shear forces to which the said wall is subjected.

3. An apparatus as defined in claim 2 wherein said second driving means includes an electric motor and said control means comprises a tacho-generator means connected in series with said electric motor and driven by said first driving means, said tacho-generator means controlling the power consumption responsive to an increasing torque load resulting from the said increasing thickness.

4. An apparatus as defined in claim 2 wherein said second driving means comprises a hydraulic motor, gear means connecting said motor to said winding roll and a pressure fluid circuit means providing a flow of fluid to said hydraulic motor, and said control means regulates the flow of fluid within said pressure fluid circuit means to control the driving power of said hydraulic motor.

5. An apparatus as defined in claim 2 wherein said means for monitoring includes a feeler roller engaging said winding roll, said roller activates said control means in response to the increasing wall thickness,

said second driving means comprises a hydraulic motor, gear means connecting motor to said winding roll and a pressure fluid circuit means providing a flow of fluid to said hydraulic motor, and said control means regulates the flow of fluid within said pressure fluid circuit means to control the driving power of said hydraulic motor.

6. An apparatus as defined in claim 2 wherein said second driving means comprises a hydraulic motor, gear means connecting motor to said winding roll

and a circuit means providing a pressure fluid supply to said hydraulic motor, said control means regulates the supply of fluid within said pressure fluid circuit means to control the driving power of said hydraulic motor, said control means having a time switch, and further including means responsive to said time switch for shutting off said supply when said monitoring means has indicated the desired thickness of said wall has been reached and said hollow cylinder has been removed.

7. An apparatus as defined in claim 3 wherein said electric motor is a direct current motor, said control means including a generator means for generating the armature voltage of said direct current motor, and

said control means further including means for connecting said tacho-generator means for generating the field voltage for said generator.

8. An apparatus as defined in claim 7 wherein said second driving means includes a reduction gearing means and means for connecting said gearing means in series with said direct current motor and said winding roll.

9. An apparatus as defined in claim 4 wherein said control means includes a pressure-regulating valve for controlling said flow of fluid, a feeler lever for activating said valve, a centrifugal governor, and a vertically movable stop arm interposed between said centrifugal governor and contacting said feeler lever for activating said valve, said centrifugal governor being responsive to said shaft of said winding roll and activating said pressure-regulating valve by way of the said stop arm.

10. An apparatus as defined in claim 5 including a pair of vertically movable swinging arms which support said winding roll,

said control means further includes a cam rail and a pressure-regulating valve for controlling the flow of fluid and a feeler lever,

said cam rail being located on one of said swinging arms and in contact with said feeler lever, said feeler lever being mounted within said pressure-regulating valve, and means for transmitting change in pressure to said pressure fluid circuit means.

11. An apparatus as defined in claim 6 wherein said control means comprises a control pump located in said pressure fluid circuit means, an electric motor for driving said control pump, a means connecting said time switch to said electric motor,

a piston pump having a variable stroke volume, said piston pump located in said pressure fluid circuit means and acting on a pressure regulator having an adjusting piston means for acting on said piston pump,

said control pump delivering pressure oil to move said adjusting piston means until said time switch stops power to said electric motor for driving said control pump.

12. An apparatus as defined in claim 11 including a pair of supporting arms mounted on a frame and supporting said winding roll, a limit switch mounted on said frame, means for connecting said limit switch to activate said time switch, and means for operating said limit switch being mounted on one of said supporting arms.

13. An apparatus as defined in claim 6 wherein said means for monitoring includes a microswitch for disconnecting said time switch operably in contact with said wall having an increasing thickness.
